CLAIM

We claim the ornamental design for a cooking pot with a lid, as shown and described.

DESCRIPTION

FIG. 1 is a top plan view of a cooking pot with a lid of the claimed design;

FIG. 2 is a front elevational view of the cooking pot with a lid shown in FIG. 1;

FIG. 3 is a rear elevational view of the cooking pot with a lid shown in FIG. 1;

FIG. 4 is a perspective view of the cooking pot with a lid shown in FIG. 1;

FIG. 5 is a left side elevational view of the cooking pot with a lid shown in FIG. 1;

FIG. 6 is a right side elevational view of the cooking pot with a lid shown in FIG. 1; and,

FIG. 7 is a bottom plan view of the cooking pot with a lid shown in FIG. 1.

The ornamental design which is claimed is shown in solid lines in the drawings. The broken lines in the drawings are for illustrative purposes only and form no part of the claimed design.

1 Claim, 7 Drawing Sheets
